UNITED STATES PATENT OFFICE.

JOHN JAMES WARREN, OF BROWNVILLE, NEW YORK, ASSIGNEE TO HARMON PAPER COMPANY, OF BROWNVILLE, NEW YORK, A CORPORATION OF NEW YORK.

WALL-PAPER AND METHOD OF MAKING IT.

1,344,570.

Specification of Letters Patent. Patented June 22, 1920.

Application filed August 14, 1918. Serial No. 248,804.

To all whom it may concern:

Be it known that I, JOHN J. WARREN, a citizen of the United States, residing at Brownville, in the county of Jefferson, State of New York, have invented certain new and useful Improvements in Wall-Paper and Methods of Making It; and I do hereby declare the following to be a full, clear, and exact description of the invention, such as will enable others skilled in the art to which it appertains to make and use the same.

The present invention relates to methods of making wall paper with a cloud effect of visionary depth, and it also relates to the wall paper produced by such methods.

The invention is based on the discovery that a wall paper having a soft and pleasing decorative appearance, together with a texture and body making it well suited to the operation of hanging and to use as a wall covering, may be produced by flowing a thin cloud-like coating of a blending paper stock on to a paper base, the surface of which has been broken up or roughened visually by incorporating with the said surface, or with the paper base as a whole, small particles, as of wood flour, of a color contrasting with the paper base, and which interrupt the otherwise smooth light-reflecting surface thereof.

I am aware that so-called "marbleized" papers having a mottled appearance of sharp definition with the hard, cold look of marble have heretofore been produced, and have been used mainly or entirely for wrapping paper; but such papers, because of their unattractive appearance and also because of their stiffness and other undesirable physical characteristics, are unsuitable for wall papers.

I have found that the surface of the paper base may be roughened or broken up to give visionary depth to the cloud effect, producing the above mentioned soft, artistic appearance, by incorporating with the paper stock an appropriate proportion of wood flour or the like, which is preferably added to the stock immediately before the formation of the paper so that the particles of the wood flour will partially or wholly retain their contrasting color with respect to the tinted body of the paper base, or the desired surface effect may be attained by treating the surface of the paper base after

formation as by flowing the wood flour thereon. In either case the blending stock is subsequently flowed onto the broken-up surface, the paper so produced having a cloud effect of visionary depth, pleasing to the eye in that it is soft and impressionistic as a whole rather than glaring and intensely detailed.

The paper base may be formed of almost any grade of paper stock according to any suitable method of making paper, and may be of any color desired to form a suitable background for the blending stock forming the cloud effect thereon. Preferably the wood flour is mixed with the paper stock, so that the paper base is formed directly with the roughened or broken-up surface and is better adapted for hanging, and the blending stock of thin consistency to form the cloud effect is flowed onto the base so formed. After water is extracted from the paper, it is pressed and dried in the usual manner of making ordinary wall paper.

In the accompanying drawings, Figure 1 illustrates diagrammatically the arrangement of the apparatus for carrying out the method of my invention; Fig. 2 illustrates the top surface of the wall paper having the cloud effect of visionary depth in accordance with my invention, and Fig. 3 illustrates the back or bottom of the preferred form of paper base.

It will be observed from Fig. 1 that the paper stock is delivered through a pipe 1 from a source of supply (not shown) to the flat screen 2 from which the screened stock is conducted by the pipe 4 to the flow box 5, where it passes around the baffles 6 on to the Fourdrinier wire 7, in the usual manner.

Although the wood flour or other material for roughening or breaking up the surface of the paper base, when formed, may be flowed on to the surface of the paper base, I prefer to mix the wood flour or other suitable material with the paper stock and to flow the mixture on to the wire apron. Accordingly, wood flour is conducted by the pipe 8 from a source of supply (not shown) to a union with the pipe 4 so that the paper stock and wood flour pass together into the flow box 5, where they are more thoroughly admixed before flowing on to the wire apron.

The blending stock is supplied by the pipe 9 from a source of supply (not shown) to

the blending box 10, where it passes around a series of baffles 11 and thence over the apron or facing slip 12 on to the paper base formed on the wire apron, the distance between the outlets of the flow box 5 and the blending box 10, and the speed of movement of the wire apron 7 therebetween, being such that the paper base is suitably formed at the time it reaches the blending box for reception of the blending stock to produce the cloudy coating of desired appearance and effect.

When the speed of travel of the wire apron 7 is that commonly employed in the manufacture of ordinary paper, the blending box 10 is preferably located 20% to 25% of the distance between the slices 14, which level the paper base, and the couch roll 15 around which the wire apron passes, that distance, however, depending upon the freeness of the stock. The breast roll 16, the table rolls 17 and the suction boxes 18, are provided in accordance with well known practice in the art. After the paper runs off the wire apron, it is dried, pressed and rolled like other wall papers.

The paper stock is suitably colored as desired and is of about the same consistency as that used in the manufacture of wall paper or other paper. The wood flour preferably consists of about 99 to 99½% of water, and the remaining part of wood fiber ground to proper fineness. The fiber is preferably of poplar, although spruce, balm of gilead, bass wood, white wood, pine, or almost any other kind of wood is suitable for the purpose. Regulation of the proportion of paper stock and wood flour is made by means of the valve 19.

The blending stock is generally white but may be of any suitable color, and preferably it has a thin consistency represented by about 99 parts water and 1 part wood fiber ground very fine. It is desirable that the stock be delivered uniformly and in regulated amounts on to the paper base. For this purpose the blending box is provided with a number of valved inlets like 13 along the width of the wire apron and the last baffle board 11' is preferably regulatable vertically to vary the thickness of the blending stock delivered to the facing strip 12, which is preferably curved as shown to deliver the stock more uniformly

on to the paper base. This part of the apparatus is more particularly described in my co-pending application filed concurrently herewith, and is therein claimed.

By mixing the wood flour with the paper stock, rather than flowing the wood flour on to the surface thereof, the paper base has a texture and body throughout of such character as to improve the adaptability of the paper for hanging on walls. Furthermore the top surface of the paper is more uniformly broken up by the wood flour as a result of the admixture, thereby rendering the cloud effect produced by the blending stock softer, more pleasing to the eye, and giving it a greater degree of visionary depth.

It will be observed from Fig. 2 that the blending stock 20 is spread lightly on a darker background of paper base 21 broken up or roughened by a more or less regular occurrence of the wood flour particles 22, and forming thereby a cloud effect having visionary depth to a marked degree. Furthermore, the paper is soft, impressionistic and artistic, and is devoid of the harshness, sharp definition and glare characteristic of the so-called "marble" paper used for wrapping.

Fig. 3, illustrating the back surface of the paper, also serves to indicate how the wood flour particles 22 break up the reflecting surface so that the addition of the blending stock to it produces the characteristic cloud effect of visionary depth.

Having thus described my invention, what I claim is:

1. The method of making wall paper with a cloud effect of visionary depth, which consists in forming a base of paper stock combined with wood flour to break up the light reflecting surface of the paper, and flowing a blending stock on the surface thereof.

2. A wall paper having a base with a light reflecting surface broken up by woodflour, and a blending stock forming a cloud effect thereon.

3. A wall paper having a base of paper stock mixed with a material breaking up the light reflecting surface thereof, and also having a blending stock forming a cloud effect on the top surface of the base.

In testimony whereof I affix my signature.

JOHN JAMES WARREN.
